Specification of Letters Patent. Patented Nov. 15, 1910.

Application filed March 15, 1907. Serial No. 362,451.

To all whom it may concern:

Be it known that we, WILLIAM F. SELLERS, a citizen of the United States of America, residing in Wilmington, county of Newcastle, and State of Delaware, and CHARLES J. DAVIDSON, a citizen of the United States of America, residing in Milwaukee, county of Milwaukee, and State of Wisconsin, have invented a certain new and useful Improvement 10 in Boilers, of which the following is a true and exact description, reference being had to the accompanying drawings, which form a part thereof.

This invention relates to steam generating case boilers and is particularly designed for use with the box header type of water-tube boilers, though the invention in all of its aspects is not limited to such use.

The object of the invention is to improve 20 the mechanical construction of the boiler and its setting and to so arrange the parts that the durability of the boiler will be prolonged and an increased efficiency and reliability of operation will be obtained.

The various features of novelty which characterize our invention are pointed out with particularity in the claims annexed to and forming a part of this specification. For a better understanding of our invention, however, and the advantages possessed 30 by it, reference may be had to the accompanying drawings and descriptive matter in which we have illustrated and described forms in which our invention may be embodied.

Of the drawings Figure 1 is a side elevation of a boiler with the outside heat insulating covering shown in dotted lines. Fig. 2 is a perspective view of a portion of a tube and the tiling or brick in which it is totally embedded. Fig. 3 is a view similar to Fig. 2 showing a construction in which the tube is only partially embedded in the tiling. Fig. 4 is a sectional elevation of the boiler, taken 40 on the line 4-4 of Fig. 5. Fig. 5 is a sectional elevation on the line 5-5 of Fig. 4. Fig. 6 is a sectional elevation on the line 6-6 of Fig. 4. Fig. 7 is a sectional plan showing a portion of the side wall of the boiler housing. Fig. 8 is a sectional elevation showing a portion of the front header and one of its supporting columns. Fig. 9 is a sectional elevation on the line 9-9 of Fig. 8. Fig. 10 is a sectional elevation illus-

trating the details of the rear header support employed in the modified construction shown in Figs. 12 and 13. Fig. 11 is a sectional elevation taken on the line 11-11 of Fig. 13. Fig. 12 is a partial plan view of an arrangement for supporting the rear header and connecting it to the rear columns or legs, differing from the construction shown in Figs. 1 to 9 inclusive. Fig. 13 is a rear elevation of the construction shown in Fig. 12. Fig. 14 is a partial elevation showing a modified form of connection of the front header to the water legs. Fig. 15 is a sectional elevation taken on the line 15-15 of Fig. 14. Fig. 16 is a partial transverse section of the boiler containing the modification of Fig. 14, taken about midway between the two headers. Fig. 17 is a rear elevation of the rear header showing a third arrangement of supporting the rear header and connecting it to the water legs. Fig. 18 is a side elevation of the construction shown in Fig. 17.

In the form of our invention shown in Figs. 1 to 9, the boiler proper consists of a front box-like header A and a rear box-like header B, which are connected at their lower ends by the usual set of inclined water tubes C and at their upper ends by the usual horizontal steam and water drum or large tube C¹. The front header A to which the upper ends of the tubes C are connected is supported by two hollow columns or water legs D, which engage the under edge of the header at opposite sides of the boiler. Each column D is placed in communication with and mechanically connected to the header A by a nipple D¹. The rear header B is supported by two hollow columns or water legs E located one at each side of the boiler. As shown, bearing plates B¹⁰ are located between the header B and the upper ends 90 of the columns E, to permit the sliding movement between the header B and the water columns E resulting from the expansion and contraction of the boiler parts as their temperatures vary. The water columns E are connected at their lower ends by a mud drum F, having a blow-out aperture F¹. The drum F is in communication with the header B through flexible curved conduits or tubes F². The columns D and E at each side of the boiler are connected to each other by a set of inclined tubes G which

are in the same vertical plane with, and are parallel to the corresponding outside row of tubes C. It will, of course, be understood that the front header of the boiler may be 5 movably supported by the water columns and the rear header rigidly supported instead of as in the arrangement just described.

The usual abutment or wall H forms the 10 rear wall of the fire box and supports the rear ends of the grate bars H¹, the front ends of which are supported by the front wall I of the boiler. The usual diaphragms or baffles J are provided to cause the flame to 15 circulate in the manner indicated by the large arrows in Fig. 4.

The side walls of the furnace are lined by 20 blocks of heat resisting tile or brick K. As shown in Figs. 5 and 6, the tiles K are so formed that the outer halves of the outer row of tubes C and the portions of the tubes G at the rear of the wall H are partially embedded in the tiling, while the portions of 25 the tubes G at the side of the fire box are entirely embedded in the tiling.

The tiling is held in place against the tubes C and G by an outer frame-work consisting of vertical metal bars L, each of which in the form shown has a portion or 30 rib L¹ extending transversely to the side of the furnace, and having its inner edge bearing against the outer surface of the tiling, and cross bars L³, L⁴ and L⁵. From the outer edge of each rib L¹ extend flanges or 35 ribs L², which are parallel to the side of the furnace. Pads M of suitable heat insulating material are preferably inserted between the tiling and the adjacent edge of the rib L¹. In the form shown the upper cross bars 40 L³ and L⁴ are riveted at their ends to the headers A and B and the lower cross bars L⁵ are anchored in any suitable manner to the boiler structure or foundation. Between each adjacent pair of ribs L¹ and between 45 the tiling and the flanges L² are removably inserted a series of blocks N of a heat insulating material. These blocks may consist of layers N¹ of an asbestos composition having air cells N² formed in them. 50 Preferably an air space O is formed between the tiling and the blocks N. The blocks and the tiling may be spaced apart to form the air space O, by the spacers O¹ which may be in the form of lugs formed 55 either on the tiling or on the blocks. The boiler as a whole may be covered by a jacket or coating of a heat insulating plaster or compound P. It will be understood that 60 the boiler is connected at its rear end to a source of cold water in any suitable manner (not shown in the drawings).

With the construction described the circulation through the tubes G is as follows: Relatively cold water enters the drum F 65 from the header B through the tubes F¹.

From the drum F water passes into the columns E, and from them through the tubes G and water columns D into the header A. The circulation of the water through the tubes G not only increases the capacity of 70 the boiler by increasing the effective heating surface, but also prolongs the life of the tiling by withdrawing heat from it as well as directly from the flame. The water columns and tubes serve, therefore, not only 75 as an effective support for the boiler setting, but also as an efficient feed water heater, while at the same time they make the boiler more durable.

The boiler housing described is simple and 80 relatively cheap to construct, possesses good mechanical and heat insulating properties, and may be repaired with comparative ease.

Instead of supporting the rear header of the boiler from the rear legs E, we may support the header from the foundation work, 85 as illustrated in Figs. 10 to 13, inclusive, in which the rear header is provided with a saddle B² having bars B³ secured to it to form a seat for a rocker B⁴ the lower end of 90 which is seated in a support B⁵, secured to a pier H¹ at the rear end of the boiler. As shown the rocker B⁴ is in the form of a bar having its upper and lower edges rounded. This construction is one found to be highly 95 satisfactory in taking care of the movement of the rear header, due to the expansion and contraction of the boiler parts, as the temperature of the boiler changes.

In the form of our invention shown in 100 Figs. 10 to 13, inclusive, each of the two rear legs E is connected to the header by a flexible connection F³ made up of jointed piping. In this form the drum has been dispensed with and F⁴ represents the connection 105 for a blow-off cock. The water is supplied to the boiler either directly to the rear header B or through the water legs E, in any suitable manner (not shown in the drawings).

Under some conditions we find it desirable to make the fire box wider than the boiler proper. One means of accomplishing this is illustrated by the construction shown in 115 Figs. 14 to 18, where the tubes G and front and rear water legs D and E, at one side of the boiler are not in the same plane with the outer row of tubes C but are at one side of said plane. With this construction the front legs D are connected to the header A by 120 means of horizontally extending hollow trunnions or nipples A¹, having flanges A² secured to the header, which trunnions or nipples extend laterally into the legs D through openings formed to receive them.

The rear header may be supported in the manner illustrated in Figs. 17 and 18, where each leg E is provided with a pintle or trunnion E³ and the header B is provided with a similar pintle or trunnion E⁴. A 125

rocker plate E^2 connects each pair of bosses, being provided with a lower aperture receiving the pintle E^3 , and an upper aperture receiving the pintle E^4 . In this form of our

5 invention the legs E are connected to the header by the jointed piping F^3 , as in the construction shown in Figs. 10 to 13, and, of course, the rocker construction illustrated best in Fig. 10, which arrangement we regard as the preferable form of support for 10 the rear header, may be employed with the laterally displaced legs E of Fig. 17, instead of the pintles E^3 and E^4 and the rockers E^2 .

15 Where the tubes G are spread apart the single vertical tile retaining parts L of the construction shown in Figs. 1 to 9, inclusive, are replaced by upper bars L^6 at the sides of the tubes C and lower bars L^7 at the sides 20 of the tubes G . The lower ends of the bars L^6 are connected to a cross bar L^9 and the upper ends of the bars L^7 are connected to a cross bar L^{10} . Short horizontal bars L^8 connect the cross bars L^9 and L^{10} .

25 While the forms of our invention disclosed have been found in actual practice to be very satisfactory, it will be readily understood by those skilled in the art that changes may be made in the form of our invention without departing from its spirit.

Certain novel features in the construction and arrangement of the furnace housing disclosed but not claimed herein are claimed in my copending application, Serial 35 No. 488,834, filed April 9, 1909, as a division of this application.

Having now described our invention, what we claim as new and desire to secure by Letters Patent is,

40 1. In a boiler, a pair of box headers, tubes connecting them, a pair of hollow columns adjacent each header, tubes connecting each column with a column for the other header and connections between each header and the 45 adjacent column, the connections between one header and the adjacent columns being flexible.

2. In a boiler, a pair of box headers, tubes connecting said headers, a pair of hollow columns extending downwardly from each header and arranged one at each end of the header, nipples connecting one header with the adjacent columns, flexible piping connecting the other header and the corresponding columns, and tubes at the side of the fire box connecting each column adjacent one header with the corresponding column adjacent the other header.

3. In a boiler, a pair of headers, a set of 50 inclined tubes connecting them, hollow columns arranged two at each side of the boiler, one at each end of each header, said columns extending from the headers to the floor level, other inclined tubes connecting said columns, provisions for obtaining a water

circulation through said columns and the tubes connecting them, a furnace lining consisting of tile, in which the side tubes of said set of tubes and said other tubes are embedded, the tubes adjacent the fire box 70 being entirely embedded in said tiling and the remaining portions of the tubes having inner surface portions exposed.

4. In a boiler, a pair of headers, a set of inclined tubes connecting them, hollow columns arranged two at each side of the boiler, 75 one at each end of each header, said columns extending from the headers to the floor level, other inclined tubes connecting said columns, provisions for obtaining a water 80 circulation through said columns and the tubes connecting them, a furnace lining consisting of tile, in which the side tubes of said set of tubes and said other tubes are embedded, the tubes adjacent the fire box 85 being entirely embedded in said tiling and the remaining portions of the tubes having inner surface portions exposed, and a metal bar framework for holding said tiling against said tubes.

5. In a boiler, a pair of headers, inclined tubes connecting them, hollow columns at the sides of the boiler, one extending downwardly from each end of each header, inclined tubes connecting said columns, provisions for obtaining a water circulation 95 through said columns and the tubes connecting them, a furnace lining consisting of tile, in which the tubes at the side of the fire box are wholly embedded and in which the retaining framework for said tiling, comprising metal bars, is located and heat insulating blocks slidingly received between each pair of adjacent bars.

6. In a boiler, a pair of headers, inclined 105 tubes connecting them, hollow columns at the sides of the boilers, one extending downwardly from each end of each header, inclined tubes connecting said columns, provisions for obtaining a water circulation 110 through said columns and the tubes connecting them, a furnace lining consisting of tile, in which the tubes at the side of the fire box are wholly embedded and in which the remaining portion of the tubes are partially embedded, a retaining framework for 115 said tiling, comprising vertical bars, heat insulating blocks slidingly received between each pair of adjacent bars, and means for spacing said blocks away from said tiling.

7. In a boiler, a pair of headers, inclined tubes connecting them, hollow columns at the sides of the boiler, one extending downwardly from each end of each header, inclined tubes connecting said columns, a furnace lining consisting of tile, in which the tubes at the side of the fire box are wholly embedded and in which the remaining portion of the tubes are partially embedded, a retaining framework for said tiling, com- 125

prising vertical bars, heat insulating blocks slidingly received between each pair of adjacent bars, and means for spacing said blocks away from said tiling.

- 5 8. In a boiler, a pair of box headers, tubes connecting said headers, a pair of hollow columns extending downwardly from each header and arranged one at each end of the header, nipples connecting one header with 10 the adjacent columns, flexible piping connecting the other header and the corresponding columns, and tubes at the side of the fire box connecting each column adjacent one header with the corresponding column adjacent the other header, the columns at op- 15

posite sides of the boiler being spaced apart so that the tubes connecting the columns are separated by a distance greater than the distance between the opposite side tubes connecting the headers.
